United States Patent Office

Des. 187,076
Patented Jan. 19, 1960

187,076

CLOCK

Douglas W. Anderson, Palatine, and Frederick David Chapman, Chicago, Ill., assignors to Jefferson Electric Company, Bellwood, Ill., a corporation of Illinois

Application September 9, 1958, Serial No. 52,579

Term of patent 14 years

(Cl. D42—7)

FIG.1

FIG.2

FIG.3

Fig. 1 is a right side elevational view of a clock embodying our new design;

Fig. 2 is a front elevational view thereof;

Fig. 3 is a top plan view thereof.

The left side elevation view is a mirror image of the right side elevational view of Fig. 1, and the bottom is free of ornamentation.

We claim:

The ornamental design for a clock, as shown and described,
